CLAIM

The ornamental design for a water purifier, as shown and described.

DESCRIPTION

1. Water purifier

1.2 : Front

1.3 : Back

1.4 : Left

1.5 : Top

1.6 : Bottom

1.7 : Exploded

1.8 : Enlarged

The broken lines depict portions of the water purifier that form no part of the claimed design; reproduction 1.1 is a front perspective view of the water purifier; reproduction 1.2 is a front view thereof; reproduction 1.3 is a back view thereof; reproduction 1.4 is a left view thereof, where the right view is a mirror image; reproduction 1.5 is a top view thereof; reproduction 1.6 is a bottom view thereof; reproduction 1.7 is an exploded view showing a state in which the water basin is separated from the main body; reproduction

(Continued)

1.8 is a reference enlarged view showing the display above the water outlets is operated and forms no part of the claimed design.

1 Claim, 8 Drawing Sheets
